UNITED STATES PATENT OFFICE.

THEODORE H. STARK, OF NEW YORK, N. Y., ASSIGNOR TO C. BRUNO & SON, INC., OF NEW YORK, N. Y., A CORPORATION OF NEW YORK.

TUNING KEY FOR STRING INSTRUMENTS.

Application filed May 18, 1926. Serial No. 109,831.

My invention relates to a new and improved form of tuning key for string instruments.

One of the objects of my invention is to provide a tuning key for tightening the strings of musical instruments which will be self-locking and which will not require the use of any coil springs or the like.

Another object of my invention is to provide a device of this character which shall be very simple and cheap to construct and assemble and which will be very reliable in its operation.

Other objects of my invention will be set forth in the following description and drawings which illustrate a preferred embodiment of my invention, it being understood that the above general statement of the objects of my invention is intended merely to generally explain the same and not to limit it in any manner.

Fig. 1 is a side elevation.

Fig. 2 is a top view.

Fig. 3 is a section on the line 3—3 of Fig. 2.

Fig. 4 is a section on the line 4—4 of Fig. 3.

The musical instrument 1 can be of any suitable type and it is provided with strings 2 of any suitable type. The well known parts of a string instrument are not illustrated in the drawings, as in themselves they are old and well known and form no part of my invention.

The head 9 of the instrument is provided with a series of openings in which the keys are located. Assuming, for the purpose of convenience, and for defining the relative positions of the parts in the claim, that the instrument is held in the horizontal position illustrated in Fig. 1, it is clear from Fig. 3 that the underside of each said opening 16 is provided with a conical end in which the hollow friction cone 4 of the key is adapted to fit. Each key comprises a shank 15 having a non-circular cross-section, such as the square cross-section illustrated in Fig. 4. Each key is also provided with an intermediate portion 14 whose diameter is slightly

greater than the diameter of the shank 15, and each key is also provided with a head 8 whose diameter is slightly greater than the diameter of the intermediate portion 14.

The intermediate portion 14 and the head 8 each have preferably a circular cross-section. Each head 8 is provided with an opening 7 into which the end of the respective string 2 can be inserted. The diameter of the head 8 is less than the diameter of the respective opening 16, and hence a perforated washer 10 is provided whose outer diameter is slightly greater than the diameter of the opening 16 and whose inner diameter is slightly less than the diameter of the head 8. Each shank 15 is internally threaded and the finger-piece 3 of the key is held in position upon the shank 15 by means of a screw 5 which is associated with a washer 6.

The parts are assembled by placing the washer 10 in the position shown in Fig. 3, then pushing the key downwardly into the position shown in said figure, then slipping upon the said key the friction cone 4 so that it enters the respective opening 16. Then the finger-piece 3 of each key is placed into the proper position, and then by suitably tightening the screw 5 the finger-piece 3 is forced against the friction cone 4 so that said friction cone 4 makes firm frictional contact with the adjacent part of the opening 16. The key can now be turned so as to wind up the string. The screw 5 is tightened up sufficiently to cause the friction cone 4 to turn with the key at all times and irrespective of the tightness of the string. The cone 4 is made of a thin sheet of resilient metal, and since the frictional hold between said cone and the finger-piece 3 is stronger than the frictional hold between said cone 4 and the bottom of opening 16, the cone 4 turns with the key at all times. Although I have shown a cone 4 in the preferred embodiment illustrated, I do not wish to restrict myself to this specific contour. If, therefore, a key is turned so as to exert considerable tension upon the string, the tension of the string causes the friction cone 4 to press even more firmly against the respective conical face of the opening 16 and this friction causes the key to become self-locking so that the tension on the string is not lessened when the hold upon the key has been released.

It is obvious that the device embodies no coil springs or supplemental springs of any kind and that it can be made of a minimum number of parts and with great cheapness.

The head 3 is provided with a bore corresponding in shape and diameter to the shank 15, so that the top of the head cannot be pushed above the bottom of the intermediate portion 14.

I have described a preferred embodiment of my invention, but it is clear that numerous changes and omissions could be made without departing from its spirit.

10 I claim:—

In combination with a musical string instrument having a head piece provided with a bore adapted to receive a key, a key located in said bore and having a first end portion 15 projecting beyond the upper face of the head piece of the said instrument, the second end portion of the said key projecting beyond the lower face of said head piece and having an internally threaded recess in the

bottom thereof, a finger-piece for said key 20 having a bore and slidably mounted upon said second end portion of the said key, the top of the said finger-piece being located below the bottom of said head piece, a hollow and bendable friction cone 25 slidably mounted upon the said key, the bottom of the said friction cone abutting the top of the said finger-piece, the top of the said friction cone projecting into the bore of the head piece and being located below the top of the 30 said bore, the said cone having a portion thereof abutting the inner wall of said bore, and a tightening screw having a head located at the underside of the said finger piece, the shank of the said screw being located in said 35 internally threaded recess.

In testimony whereof I affix my signature.

THEODORE H. STARK.
